UNITED STATES PATENT OFFICE.

CHARLES S. C. ROCK, OF NEW YORK, N. Y.

BATH-SHOWER.

1,083,141.

Specification of Letters Patent. Patented Dec. 30, 1913.

Application filed August 30, 1913. Serial No. 787,437.

To all whom it may concern:

Be it known that I, CHARLES S. C. Rock, a subject of Great Britain, and a resident of the city of New York, borough of Manhattan, in the county and State of New York, have invented a new and Improved Bath-Shower, of which the following is a full, clear, and exact description.

This invention relates to plumbing and has particular reference to shower bath apparatus.

Among the objects of the invention is to provide a bath shower of an unusually simple and reliable construction, occupying a minimum amount of space and requiring the least amount of manipulation to bring it into or throw it out of action.

A further object of the invention is to devise an apparatus of the character mentioned which dispenses with the necessity for a hood or apron to prevent splashing of the water over the bathroom floor.

Another object of the invention is to so arrange the bath shower as to provide for a portion thereof to be utilized as a towel rack.

The foregoing and other objects of the invention will hereinafter be more fully described and claimed and illustrated in the drawings forming a part of this specification in which like characters of reference indicate corresponding parts in all the views, and in which—

Figure 1 is a perspective view showing a conventional form of bathtub with my improved bath shower arranged in operative position in connection therewith; Fig. 2 is a plan view of the shower portion of the device; Fig. 3 is a vertical section on the line 3—3 of Fig. 2, showing the relation of the spraying nozzle to the bathtub and also indicating the direction of the jets of water with respect to the tub and indicating in dotted lines the position which the said nozzle occupies when out of use; and Fig. 4 is a detail of the joint between the relatively stationary and movable parts of the tubing.

The several parts of the device may be made of any suitable materials and properly ornamented or finished, and the relative sizes and proportions, as well as the general design of the equipment, may be varied to a considerable extent without departing from the spirit of the invention hereinafter more fully set forth and specifically claimed.

At 10 I show a bathtub having the usual hot and cold water inlets 11 and 12.

The bath shower comprises two principal parts of tubing shown at 13 and 14. The tubing 13 is relatively stationary and is journaled upon a horizontal axis in a bracket 15 which is adapted to be secured in a permanent position on the vertical wall at the rear of the bathtub. Said bracket 15 is preferably made of strap metal bent in the form shown in Fig. 3 for simplicity and neatness of appearance. The bearing 15', however, of the bracket provides for rotation of the pipe 13 under certain conditions. Said pipe 13 has one end 13' extending downwardly and adapted to be connected to the delivery nozzle 16 into which the hot and cold water lines lead. Upon detaching the connection 13', the pipe 13 will be free to rotate sufficiently in the bearing 15' to allow the end 13' to drop against the side of the bathtub.

The nozzle portion of the tubing shown at 14 is substantially U-shaped, one leg of which is connected in horizontal alinement with the pipe 13. This leg of the nozzle is journaled in a bracket 17 having a bearing 17' preferably of the same character as the aforesaid bracket 15. The adjacent ends of the pipes 13 and 14 are connected by a sleeve or collar 18 having one end permanently secured as by screw threads to the inlet end of the nozzle 14 and having its other end connected to the delivery end of the pipe 13 in any suitable substantially watertight manner but providing for relative rotation between the parts. A pin 19 in the form of a screw is tapped through the end of the pipe 13 adjacent the collar 18 and is so arranged as to be struck by a shoulder 18' of the collar when the U-shaped nozzle 14 as a whole occupies a substantially horizontal plane. This manner of connecting the nozzle 14 to the pipe 13 provides for the nozzle to be turned up and back against the wall, as shown in Fig. 3 in dotted lines, when not in use, and yet leaving that portion of the tubing between the brackets 15 and 17 in a horizontal and substantially stiff position and at a convenient elevation for use as a towel rack.

The nozzle 14 in operative position lies in a plane arranged horizontally above the bathtub some six or eight inches or at a height approximately the same as a person's chin while seated within the bathtub. The size of the U-shaped nozzle, also, is such as to bring it within the bathtub flange as viewed in plan; see Fig. 2. Any drip, there-

fore, which may be formed upon or discharged from said nozzle will drip within the tub. As shown in Figs. 1 and 3, the nozzle 14 is provided with perforations on 5 its inner surface arranged preferably in two series 14^a and 14^b. The series 14^a lie in a plane coincident with the axis of the nozzle and the other series 14^b lie in a plane parallel to the first mentioned plane and below 10 the same when the device is in use. These perforations are formed radially through the wall of the nozzle and hence direct the streams of water, as shown in Fig. 3, from any point of the nozzle across toward the 15 opposite side of the tub or toward the bottom, the streams 14^c from the upper perforations crossing each other at points substantially at the height of the person's shoulders. The spray, therefore, is all directed within 20 the tub and renders the use of a curtain or apron unnecessary for the purposes of this invention. As indicated in Fig. 2, the ends of the nozzle 14 may be provided with additional perforations for the purpose of increasing 25 the amount of spray at these places, as, for instance, when the person wishes to apply the shower to his head he has but to lower his head, bringing it under the augmented spray or shower at the place indicated at 14^e. The extreme end of the nozzle 14, or that end opposite the collar 18, is preferably closed by means of a screw 30 threaded plug 20.

Having thus described my invention, I 35 claim as new and desire to secure by Letters Patent:—

1. In a bath shower, the combination of a relatively stationary pipe having a horizontal portion above the bathtub, a nozzle having 40 one portion thereof in longitudinal alinement with said horizontal portion of the pipe, a movable joint connecting the adjacent ends of said pipe and nozzle permitting the nozzle to be rotated around the axis 45 of said pipe, means to support the pipe and nozzle in position above the bathtub, and means to limit said rotation of the nozzle in a downward direction, said nozzle being provided with spraying means directed to 50 ward the interior of the tub.

2. In a bath shower, the combination with

a bathtub and means to deliver water into the same, of a water pipe adapted to be connected to the water delivering means or be disconnected therefrom, said pipe having a 55 horizontal portion above the tub, a bracket supporting the pipe and having a bearing with a horizontal axis permitting the pipe to have a certain degree of rotation therein, a nozzle having one portion in alinement 60 with the horizontal pipe portion, a movable joint connecting the same, a second bracket having a bearing in alinement with the first mentioned bearing and serving to support the nozzle so that it may rotate with respect 65 to the first mentioned pipe, said nozzle being provided with perforations leading therefrom into the tub, and means to close the end of the nozzle remote from the movable joint aforesaid.

3. In a bath shower, the combination with a relative stationary water pipe having a horizontal end, of a stop pin secured in said pipe end, a U-shaped spraying nozzle having one leg supported in alinement with the 75 horizontal end of said pipe, and a collar secured to the end of said leg adjacent the pipe constituting a watertight connection between the two parts, said collar having a shoulder adapted to impinge against said 80 pin to limit the U-shaped nozzle in a horizontal position, substantially as set forth.

4. In a bath shower, the combination of a water pipe mounted in fixed supports above the bathtub, a nozzle constituting a continuation of said pipe and extending thence around one end of the bathtub and serving to spray water received from the pipe toward the center of the bathtub, means to connect said pipe to the water supply, said 90 nozzle being movable around the axis of said pipe, and stop means to limit the movement of the nozzle and maintain it in normal horizontal operative position.

In testimony whereof I have signed my 95 name to this specification in the presence of two subscribing witnesses.

CHARLES S. C. ROCK.
